UNITED STATES PATENT OFFICE.

ANGELO P. CINQUEGRANA AND PASQUALE DE-CAPRIO, OF NATICK, RHODE ISLAND.

SMASH-PREVENTER.

1,372,217.

Specification of Letters Patent.

Patented Mar. 22, 1921.

Application filed November 11, 1919. Serial No. 337,296.

To all whom it may concern:

Be it known that we, ANGELO P. CINQUEGRANA and PASQUALE DE-CAPRIO, citizens of the United States, residing at Natick, county 5 of Kent and State of Rhode Island, have invented certain new and useful Improvements in Smash-Preventers; and we do hereby declare the following to be a full, clear, and exact description of the invention, such as will enable others skilled in the art to which it appertains to make and use 10 the same.

Our invention relates to devices for banging off the loom when an imperfect transfer 15 of the bobbin to the shuttle has been made.

Occasionally the transfer mechanism fails to push the bobbin entirely within the shuttle, but leaves a portion of the former upwardly projecting, thereby causing break 20 downs in the loom.

It has been attempted to bang off the loom by interposing a rigid arm in the path of the projecting bobbin. The rigid character of the arm has resulted in breaking the contact 25 and other parts.

The objects of our invention are to overcome the recited defects, and to attain this end in a structure adapted to facile application without alteration in the usual type 30 of looms, and in a structure inexpensive to construct and apply.

To the above ends essentially our invention consists in such parts and in such combinations of parts as fall within the scope 35 of the appended claims.

In the accompanying drawings which form a part of this specification,

Figure 1 is a plan view,

Fig. 2, a side elevation of the same structure at the left end of the lay viewed from the rear of the loom,

Figs. 3 and 4, sections on lines 3—3 and 4—4 respectively of Fig. 1, and

Fig. 5, a perspective view of the same.

Like reference characters indicate like parts throughout the views.

In the drawings 10 is the lay of a loom carrying the shuttle box 11 comprising front wall 12 and rear wall 13, the latter having 50 the web portion or top plate 14. 15 is the swell or binder. Each end of the lay member, as at 17, is cut away to allow egress from the filler carrier when attached to the sheath. 18 is the picker stick, 19 the picker, 55 20 the cushion, 21 the swell spring, 22 the bunter, 23 the lay shoulder, 24 the shuttle,

and 25 the spindle of an empty bobbin or filler carrier having a head 26. It is in conjunction with such usual well known loom parts that my device is herein set forth. 60

Near one end thereof the flat portion 14 of the top plate is slotted or cut away longitudinally, as at 27, so that the exposed edge of the web portion 13 forms a rib 28 and a shoulder 29. A belt 30 is threaded 65 or otherwise secured in the lay below the shoulder 29 and has a head 31 constituting a pivot member for a bracket 33. The latter comprises an upright portion 34 provided in this instance with a laterally offset 70 upper portion 35 carrying a horizontal arm 36 having in the form thereof herein shown a vertically offset end 37 merging in the portion 35. Near its lower end the portion 34 of the bracket has a perforation 39 75 through which loosely passes the bolt 30, thus loosely pivoting the bracket between the head 31 and the lay shoulder 23. The arm 36 is substantially at right angles to the portion 34 of the bracket and extends horizontally over the shuttle box. The portion 34 of the bracket has a transverse angular bend 41. Spaced apart cavities 44 in the arm may be present to insure clearance of the shuttle in case the height of the wall 80 13 of any particular loom is excessively low.

The bracket 33 is maintained in normal upright position against the shoulder 29 by a helical spring 47 attached at one end to a screw 51 in the lay, and engaged at its other 90 end by passing through a hole 53 in the portion 34 of the bracket.

The operation of our device is as follows: The arm 36 is during the transfer of the bobbin normally in retracted position and 95 spaced above the path of the shuttle sufficiently to permit passage of the shuttle thereunder without interference. If, however, the transfer of the bobbin is faulty, and the head 26 thereof projects above the 100 plane of the shuttle, the movement of the shuttle toward the race will cause the bobbin head 26 to strike the arm 36, and cause the bobbin spindle 25 to move downwardly and lock the shuttle in the shuttle box, as 105 shown in Fig. 3, thus preventing the shuttle from moving along the race to lay a weft thread. This failure to lay a weft thread causes the usual weft detector or weft stop to come into play thereby causing the bang- 110 off of the loom in the usual manner.

The impact of the head 26 against the arm

35 is cushioned by the spring 47, so that no jar or injury to the shuttle or loom parts results.

We claim:—

- 5 1. In combination with a loom having a shuttle box, a shuttle operating therein, and a bobbin in the shuttle, of a bracket pivotally associated with the shuttle box, an arm on said bracket overhanging the shuttle box
- 10 and spaced above the shuttle, said arm adapted to be struck by a bobbin when projecting from the shuttle, whereby to cause the arm to swing down and lock the shuttle against movement, thereby preventing the shuttle
- 15 from laying the weft strand, as a consequence of which the weft stop will cause the banging off of the loom and means connect-

ing said bracket with some fixed part to hold the bracket normally in upright position.

2. In combination with a loom having a shuttle box, a shuttle operating therein, and a bobbin in the shuttle, of a bracket pivotally associated with the shuttle box, and an arm projecting at substantially right angles from said bracket, and a spring connected with said arm and with some relatively fixed part for holding said arm and bracket in an initial position and adapted to yield and permit the movement of the same when the arm is struck by a projecting bobbin.

In testimony whereof, we affix our signatures.

ANGELO P. CINQUEGRANA.
PASQUALE DE-CAPRIO.
